(57) **CLAIM**

The ornamental design for a portable information handling system, as shown and described.

DESCRIPTION

FIG. 1 is an angled frontal perspective view of the portable information handling system comprising the present invention the broken lines being shown for illustrative purposes only and form no part of the claimed design.

FIG. 2 is a front elevation view thereof;

FIG. 3 is a right side elevation view thereof;

FIG. 4 is a left side elevation view thereof;

FIG. 5 is a back elevation view thereof;

FIG. 6 is a top plan view thereof;

FIG. 7 is a bottom plan view thereof;

FIG. 8 is an angled frontal perspective with detached keyboard view thereof; and,

FIG. 9 is a top, frontal and left side perspective view thereof shown closed.
